SAYERS DRAY EUBANKS, OF CONCORD, NORTH CAROLINA, ASSIGNOR TO WILLIAM BAXTER BRUTON AND ALEXANDER ROBINSON HOWARD, BOTH OF CONCORD, NORTH CAROLINA.

LUG-STICK FOR LOOMS.

1,300,147.

Specification of Letters Patent.

Patented Apr. 8, 1919.

Application filed September 4, 1918. Serial No. 252,660.

To all whom it may concern:

Be it known that I, SAYERS DRAY EUBANKS, a citizen of the United States, residing at Concord, in the county of Cabarrus 5 and State of North Carolina, have invented certain new and useful Improvements in Lug-Sticks for Looms, of which the following is a specification.

This invention has reference to lug sticks 10 for use in looms, and its object is to provide a device to replace the lug straps in common use employed for impelling the picker stick.

It has heretofore been customary to make the lug straps of wood, canvas and metal, 15 the construction being relatively expensive and short-lived.

By this invention the lug strap is replaced by a lug stick, so called because it may be made entirely of wood with the result 20 that the life of the device is very greatly prolonged while the cost of the device is very largely reduced.

The invention will be best understood from a consideration of the following detailed description taken in connection with the accompanying drawing forming part of this specification, with the understanding, however, that the invention is not confined to any strict conformity with the showing 30 of the drawing but may be changed and modified so long as such changes and modifications mark no material departure from the salient features of the invention as expressed in the appended claim.

35 In the drawing:

Figure 1 is a side elevation of a lug stick as applied to a picker stick.

Fig. 2 is a plan view of the lug stick on a larger scale than that of Fig. 1.

40 Fig. 3 is a section on the line 3—3 of Fig. 2.

In Fig. 1 there is shown a picker stick 1 which may be of ordinary construction and mounted in the usual way, wherefore, no 45 particular description of the picker stick is needed.

In order to actuate the picker stick to throw the shuttle, there is provided a device which, because of its general construction, 50 has heretofore been known as a lug strap. Such lug strap comprises an elongated wooden member to one end of which one end of a link is attached, the link receiving motion from a suitable part of the loom structure to intermittently move the picker stick

forcefully so as to throw the shuttle, the movements of the parts being properly timed for the purpose. Attached to the other end of the wooden member is a flexible member in the form of a loop with the free ends 60 clamped to the wooden member by cheek plates and a bolt traversing the cheek plates, the wooden member and elongated slots through the free ends of the legs of the loop. In this manner the strap is formed into a 65 closed loop and the length of the strap may be determined by moving the legs of the loop along the wooden member, this being permitted by the slots.

Such a lug strap has a limited life in action, the strap wearing out in about six weeks and the loom must be stopped while the worn out fabric is replaced with new fabric.

With this invention, the customary lug 75 strap formed of five separate pieces is replaced by a one-piece structure which may be made entirely of wood and, while susceptible of manufacture of other materials, is preferably constructed of wood, experience having demonstrated that such a wooden structure has long life and may be made very cheaply. The life of the wooden lug stick may extend into years without necessity of replacing it and such wooden one-piece lug sticks may be manufactured at 80 small expense.

The lug stick of the invention comprises an elongated body member 2 of a length corresponding to the ordinary lug strap, one end 3 of the stick being flattened and formed with an elongated slot or eye 4. The other end of the stick 2 is also elongated, as shown at 5, and is provided with a slot 6 elongated in the direction of the length of 85 the stick and of a width to snugly yet freely receive the picker stick 1 which traverses the slot 6. The walls of the slot 6 may be slightly rounded to avoid any sharp corners.

In the lug stick of the invention the slot 6 is of constant length, while in the lug straps, as heretofore used, the length of the loop through which the picker stick extends is adjustable, adjustment being necessary to regulate the throw of the shuttle. In order 100 to provide for the throw of the shuttle with the lug stick of the invention, the elongated slot 4 is used. A yoke 7 is applied to the end 3 which is suitably thinned and flattened and a bolt 8 traversing the legs of the yoke and 110

the slot 4 holds the yoke 7 in adjusted positions. A link 9 is secured to the lug stick 2 by the yoke 7 and this link is driven in any suitable manner by the mechanism of the loom so that impulses are imparted to the picker stick to throw the shuttle in the customary way across the loom.

What is claimed is:—

A one-piece wooden lug stick for looms

having an elongated longitudinally disposed slot near one end to be traversed by a picker stick, and the other end having an elongated longitudinally disposed slot for the attachment of an actuating link for the lug stick in adjustable relation thereto.

15

In testimony whereof I affix my signature.

SAYERS DRAY EUBANKS.

Copies of this patent may be obtained for five cents each, by addressing the "Commissioner of Patents, Washington, D. C."
